UNITED STATES PATENT OFFICE.

DOUGLAS L. SAUERHERING, OF WAUSAU, WISCONSIN, ASSIGNOR OF ONE-HALF TO
WILLIAM W. ALBERS, OF WAUSAU, WISCONSIN.

SWIVEL CONNECTION.

Application filed March 10, 1920. Serial No. 364,812.

To all whom it may concern:

Be it known that I, DOUGLAS L. SAUERHERING, a citizen of the United States, and a resident of Wausau, in the county of Marathon and State of Wisconsin, have invented certain new and useful Improvements in Swivel Connections, of which the following is a specification.

My present invention relates generally to electric connections and more particularly to connector for electric cords, my object being the provision of a simple effective swivel connection for use in electric light and other cords to obviate twisting and tangling and in particular to obviate kinking and breaking, and a further object is the provision of a device of this nature in which pulling strains will be taken up through means clamped to integral portions of wire sections apart from the connected extremities of the wires.

In the accompanying drawing which illustrates my invention and forms a part of this specification,

Figure 1 is a side view of the complete device,

Figure 2 is a vertical longitudinal section, and

Figure 3 is a sectional end view looking at the right hand end of the device as in Figures 1 and 2.

Figure 4 is an end view,

Figures 5 and 6 are detail sections through the connected ends of the wires, and

Figure 7 is a detail cross section taken on line 7-7 of Figure 5.

According to my invention sections of electric light or other cords, as indicated at 10 and 11, are separated adjacent to their ends to be connected in order to expose their individual wrapped wires 12, 13, 14 and 15, the end of the wire 12 being connected by a set screw or like fastening member as at 16 to one end of a metal contact plug 17 rotatably extended within a tube 18, through the opposite constricted end of which tube a pin 19 is movable. Into the outer end of this pin, the wire 13 of cord 11 is secured as by means of a set screw or like fastening member 20, the opposite or inner end of pin 19 being provided with an enlarged head 21 located within the tube 18 and in engagement with the adjacent end of plug 17. Around the pin 19 is a coil spring 22 which is slightly compressed between the con-

stricted end of the tube 18 and the enlarged head 21 the pressure being sufficient to maintain engagement between the latter and the plug 17. The ends of the electric cords 10 and 11 are thus spaced apart in their connected relation, and these spaced apart ends are spanned by a pair of tubular sheaths 23 and 24 of insulating material, whose outer ends respectively telescope the adjacent ends of the cords 10 and 11 whose inner ends are in substantially abutting relation between the cord ends and adjacent to the end of cord 10. For this purpose sheath 24 is substantially greater in length than sheath 23 so as to receive within its bore the tube 18 with the plug 17 and the contact pin 19 therein.

The outer portions of the sheaths 23 and 24 are preferably slotted as indicated at 25 and are preferably surrounded by the end portions 26 and 27 of the two metallic swivel holders, one of which has an annular outstanding flange 28 at its inner end supporting an annularly grooved inner ball race 29, and the other of which has an annulus 30 provided with a flange 31 supporting an annularly grooved outer ball race 32 between which and the ball race 29 an annular series of anti-friction balls 33 are disposed and have lateral bearing against portions of both rings.

The annulus 30 is connected to the tubular portion 26 of its respective swivel member by inclined radiating arms 34, and clamps 35 and 36 are respectively engaged and adjusted around the slotted outer ends of portions 26 and 27 to securely clamp the outer portions of the two swivel members to the ends of the cords 10 and 11 so as to thus rigidly engage the cord ends, apart from their extending wires 12, 13, 14 and 15 and take up pulling strains, that is lengthwise of the complete cord, without subjecting the said wire ends thereto.

By reference to Figures 1 and 2 in particular it will be noted that the connections of wires 12 and 13 respectively to the plug 17 and the contact pin 19, are located inwardly beyond the two swivel supporting clamps 35 and 36, the other ends 14 and 15 of the wires being extended outwardly through the sheaths 23 and 24 and soldered or otherwise rigidly connected to the tubular portions 26 and 27 of the swivel members also at points inwardly beyond the two clamps.

Thus it will be noted that all pulling

2

strains will be taken up through the ball tions surrounding the cord sections within 40
bearings and that the two sections 10 and 11 the tubular portions of the swivel members, 40
of the cord will be free to rotate with respect clamps around the tubular portions of the
to one another particularly in view of the swivel members for clamping the same and
5 fact that both the swivel forming members, the said sheaths to the cord sections, said
to which wires 14 and 15 are connected, and sheaths being provided with openings
the plug 17 and contact pin 19 to which 45
wires 12 and 13 are connected, have movable through which certain of the extending wires
engagement in the same transverse plane. of the cord sections project outwardly for
connection to said swivel members, a tube
in one of the sheaths, and a plug and a con- 50
tact pin engaging one another and revolvably
10 The relief of strain from the wire ends 12 disposed in the tube, and to which the other 50
and 13 obviously permits the plug 17 and wires of the said cord sections are connected
ball 21 to remain in contact by virtue of the as described.

15 The relief of strain from the wire ends 12
tract to any considerable extent from the
tube 18.

20 In constructing the connector I propose,
the outer metal holders with their ball races
may be first assembled. After passing one of
the wires, that is the wire 10 or the wire 11,
25 through the assembled metal parts, the wire
attaching parts 17 and 18 are assembled
within the slotted sheath sections 23 and 24
and these parts are then shifted lengthwise
25 into the metal holders and the clamps 35
and 36 then tightened so as to secure the
parts in the assembled position.

I claim:

1. A swivel connection for axially alined
30 electric cords having their wire ends extend-
ing there beyond, consisting of a pair of
swivel forming members having outer tubu-
lar portions and inner opposing flanged por-
tions, ball races supported in opposing rela-
35 tion by said flanged portions, an annular
series of balls between said races, a pair of
tubular insulating sheaths axially alined
within the swivel members and having por-

tions surrounding the cord sections within
the tubular portions of the swivel members, 40
clamps around the tubular portions of the
swivel members for clamping the same and
the said sheaths to the cord sections, said
sheaths being provided with openings
through which certain of the extending wires 45
of the cord sections project outwardly for
connection to said swivel members, a tube
in one of the sheaths, and a plug and a con- 50
tact pin engaging one another and revolvably
disposed in the tube, and to which the other 50
wires of the said cord sections are connected
as described.

2. A swivel connection for axially alined
electric cord sections having extended wire
ends, which consists of swivel forming mem- 55
bers, clamps connecting said members at their
outer ends to the cord sections and inwardly
beyond which clamps the said wire ends pro-
ject, said swivel members having inner op-
posing and relatively rotatable portions, 60
anti-friction bearing means between and con-
necting said inner portions of said swivel
members, tubular insulating sheaths connect-
ed to the cord sections and extending through
the said swivel members in axially alined 65
endwise abutting relation, said sheaths hav-
ing openings through which certain of the
wire ends project outwardly for connection
to the swivel members at points inwardly be-
70 yond the clamped portions of the wires, and
connecting means within and protected by
the said sheaths for the other wires of the
cord sections, said last named means includ-
ing revolvably engaged parts.

DOUGLAS L. SAUERHERING.
